Primary Examiner — Jonathan J Han*Assistant Examiner* — Amanda J Berlinski(57) **CLAIM**

The ornamental design for a light therapy device, as shown and described.

DESCRIPTION

FIG. 1 is a front perspective view of a light therapy device showing my new design.

FIG. 2 is a rear perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof; and,

FIG. 9 is an enlarged view of a portion indicated with "9" in FIG. 2.

The dash-dash broken lines illustrate portions of the light therapy device that form no part of the claimed design. The dot-dash lines in FIGS. 2 and 9 are included to identify areas of enlargement and form no part of the claimed design.
